[57] ABSTRACT

A switch, of pole-mounted type, adapted for connection, in an electrical power supply system, between a feed cable and a load cable; the switch, in one position, normally providing direct connection between the feed cable and the load cable, and, in another position, breaking such direct connection and establishing a by-pass connection—including a booster transformer—between the feed cable and load cable whereby to “boost” the current value in said load cable under a condition of undue voltage drop therein. The switch also provides a shunt operative to prevent the load cable from being taken completely out-of-circuit as the switch is actuated from said one position to such other position; said shunt—which includes a resistor—also serving to preload the booster transformer, with less than the full feed voltage, before the switch closes in such other position.

*Fig. 3**Fig. 4**Fig. 5**Fig. 6*## BOOSTER TRANSFORMER SWITCH

BACKGROUND OF THE INVENTION

When the current value in a load cable, of an electrical power supply system, substantially reduces as a result of the demand thereon, the voltage drop is compensated for by means of a booster transformer then interposed between the feed cable and such load cable. This must be accomplished by a switch adapted for the purpose, and the present invention was conceived in the course of efforts to produce such a switch of pole-mounted type and one having commercial advantage both from the standpoint of ready manufacture and effective operation.

SUMMARY OF THE INVENTION

The present invention provides, as a major object, a pole-mounted dual-position switch adapted for manual actuation between one position in which the switch provides a direct connection between a feed cable and a load cable, and another position in which said direct connection is broken and a by-pass connection—including a booster transformer—is established between the feed cable and load cable for the purpose of "boosting" the voltage in said load cable when an undue voltage drop occurs in the latter.

The present invention provides, as another object, a switch, as above, which includes a shunt automatically brought into play when the switch is actuated from said one position to such other position; the function of the shunt, which includes a resistor, being to prevent the load cable from being taken completely out-of-circuit as the switch is so actuated, and to pre-load the booster transformer, with less than full feed voltage, before the switch closes in such other position.

The present invention provides, as a further object, a booster transformer switch which is designed for ease and economy of manufacture.

The present invention provides, as a still further object, a practical, reliable, and durable booster transformer switch, and one which is exceedingly effective for the purpose for which it is designed.

BRIEF DESCRIPTION OF THE DRAWINGS

FIG. 1 is a side elevation of the switch in its position providing direct connection between the feed cable and load cable.

FIG. 2 is a top plan of the switch as in FIG. 1.

FIG. 3 is an end elevation of the same.

FIGS. 4, 5, and 6 are diagrammatic illustrations of certain positions of the switch.

DESCRIPTION OF THE PREFERRED EMBODIMENT

Referring now more particularly to the drawings and to the characters of reference marked thereon, the switch comprises, on a suitable mount 1 on a cross arm 2 of the pole P, a pair of spaced end-to-end insulators 3 and 4 disposed substantially horizontally; the insulator 3 being rotatably secured at its inner end to the mount 1 in a known manner, and rotation of such insulator being accomplished by the usual lever 5 adapted to connect to a push-pull rod R. At its outer end, the insulator 3 is connected to the feed cable 6 of the circuit phase to which the switch is related. The insulator 4, which is non-rotatably secured to the mount 1, is connected at the outer end to the load cable 7.

The rotatable insulator 3 carries a generally L-shaped arm 8 having a blade 9 at its outer end; such blade normally engaging in a clip 10 on the outer end of a generally L-shaped arm 11 carried by the non-rotatable insulator 4. As shown, the feed cable 6 and load cable 7 are electrically connected to the blade 9 and clip 10, respectively.

The arms 8 and 11, which are opposed, are shaped so that—upon part-circle rotation of insulator 3 and arm 8 by lever 5 and in a given direction—blade 9 escapes clip 10 and swings upwardly and inwardly through an arc in the vertical longitudinal plane of the cross arm 2.

A third insulator 12 is secured to the mount 1 and projects upwardly adjacent the insulators 3 and 4 and at a right angle to the axis thereof; the insulator 12 being fitted at its outer end with a short, rigid arm 13 which carries a clip 14 at its outer end. The clip 14 is disposed in the same transverse vertical plane as the clip 10 and faces the latter in spaced relation. The arrangement is such that—upon rotation of insulator 3 in the proper direction and resultant swinging of the arm 8—blade 9 escapes from clip 10 and engages in clip 14.

When the blade 9 is fully engaged in clip 10, the switch—which is then in its normal position—provides a direct connection between the feed cable 6 and the load cable 7. See, for example, FIGS. 2 and 4. However, upon the occurrence of a load condition which causes an undue voltage drop in the load cable 7, the switch is actuated to cause blade 9 to escape clip 10 and fully engage in clip 14 as previously described. See FIG. 6. When blade 9 is so engaged in clip 14, a by-pass circuit or connection—including a pole-mounted booster transformer 15 shown diagrammatically in FIGS. 2, 4, 5, and 6—is established between the feed cable 6 and load cable 7.

More particularly, such by-pass connection includes, together with blade 9 and clip 14, leads 16 which couple the clip 14 to one side of the transformer, and a lead 17 which extends from the other side of the transformer to the load cable 7.

Thus, when the described by-pass circuit or connection is closed and operative, the booster transformer 15 functions to return the voltage in load cable 7 to the requisite value. Thereafter, when the load condition which caused the undue voltage drop is relieved, the switch is returned to its normal position with blade 9 free of clip 14 and engaged in clip 10.

In order to preclude the load cable from being taken wholly out-of-circuit when the switch is actuated from its direct-connection position (blade 9 engaged in clip 10), to its by-pass or "booster" position (blade 9 engaged in clip 14), and further to pre-load the transformer 15 with less than full feed voltage before the switch closes in said by-pass position, a shunt is provided as follows:

An oval-shaped, spring blade wiper 18 is disposed adjacent and parallel to the transverse vertical plane occupied by the clips 10 and 14; such wiper 18 being positioned for electrical-contact engagement by the blade 9 as the latter swings in an arc between said clips. The configuration, size, and position of the wiper 18 is such that the blade 9, as it is so swung, engages with such wiper 18 before total disengagement from clip 10 as shown in broken lines in FIG. 5, and initially engages with the clip 14 before total disengagement from said wiper as shown in broken lines in FIG. 6.

The wiper 18 is suspended in position by a bracket 19 on the adjacent end of a dielectric rod 20 which, in turn, is held in a fixed position by a bracket 21 secured on an arm 22 radiating from the outer end of insulator 12; the arm 22 being in electrical connection with the lead 16 running to transformer 15.

A resistor 23 of predetermined capacity is attached to, and spans between, the brackets 19 and 21 whereby to establish a resistor circuit between the wiper 18 and the lead 16.

From the above description of the shunt, it will be recognized that as the switch is actuated from its direct-connection position to its by-pass position, there is no interruption of current flow from the feed cable 6 to the load cable 7; the blade 9, before it escapes the clip 10, engaging the wiper 18 so that when such escape takes place a circuit—at less than full feed voltage—is established through the resistor 23 to the booster transformer 15 (to pre-load the same), and thence to said load cable 7. Then, after the blade 9 initially engages clip 14, said blade escapes the wiper 18 and makes full engagement with clip 14 whereby the shunt is dropped out, the by-pass circuit is completed to the transformer, and the latter is energized directly from the feed cable 6.

From the foregoing description, it will be readily seen that there has been produced such a booster transformer switch as substantially fulfills the objects of the invention, as set forth herein.

I claim:

1. A pole-mounted switch adapted for use in connection with a feed cable, a load cable, and a booster transformer; comprising a mount, a pair of insulators secured to and projecting from the mount, one insulator being rotatable and the other insulator non-rotatable, arms on such insulators extending to outer end terminations normally in adjacent relation, a blade on the outer end of the arm corresponding to said one insulator, a clip on the outer end of the arm corresponding to said one insulator, the blade normally engaging in the clip but being disengagable therefrom upon part-circle rotation of said one insulator in a predetermined direction, the feed cable being connected to said one insulator and the blade, the load cable being connected to said other insulator and the clip, a third insulator secured to and projecting from the mount in spaced relation to said pair of insulators, a supporting arm on and extending from the third insulator, a separate clip on such supporting arm and disposed thereby for engagement by said blade upon such part-circle rotation of said one insulator and resultant swinging of the blade away from said first-named clip, there being a by-pass circuit leading from said separate clip to the load cable, the booster transformer being interposed in such by-pass circuit, one bracket supported from said third insulator, a second bracket disposed in spaced relation to said one bracket, a dielectric rod fixed with and spanning between such brackets, a wiper secured in connection with said second bracket and positioned for contact by the blade during said swinging thereof, the wiper being formed and disposed so that the blade, upon such swinging thereof, makes contact with the wiper before disengagement from said first-named clip and thereafter makes contact with said separate clip before disengagement from said wiper, a resistor connected to and spanning between said brackets, and means providing electrical connection between said one bracket and the booster transformer.

2. A pole-mounted switch adapted for use in connection with a feed cable, a load cable, and a booster transformer; comprising a mount, a pair of insulators secured to and projecting from the mount, one insulator being rotatable and the

- other insulator non-rotatable, arms on such insulators extending to outer end terminations normally in adjacent relation, a blade on the outer end of the arm corresponding to said one insulator, a clip on the outer end of the arm corresponding to said other insulator, the blade normally engaging in the clip but being disengagable therefrom upon part-circle rotation of said one insulator in a predetermined direction, the feed cable being connected to said one insulator and the blade, the load cable being connected to said other insulator and the clip, a third insulator secured to and projecting from the mount in spaced relation to said pair of insulators, a supporting arm on and extending from the third insulator, a separate clip on such supporting arm and disposed thereby for engagement by said blade upon such part-circle rotation of said one insulator and resultant swinging of the blade away from said first-named clip, there being a by-pass circuit leading from said separate clip to the load cable, the booster transformer being interposed in such by-pass circuit, a shunt comprised of a wiper positioned for contact by the blade during said swinging thereof, and a shunt circuit extending from the wiper to the booster transformer.
3. A switch, as in claim 2, in which the wiper is formed and disposed so that the blade, upon such swinging thereof, makes contact with the wiper before disengagement from said first-named clip.
4. A switch, as in claim 3, in which the wiper is formed and disposed so that the blade, upon such swinging thereof, makes contact with said separate clip before disengagement from said wiper.
5. A switch, as in claim 2 including a resistor interposed in such shunt circuit.
6. A switch, as in claim 2 in which the wiper is formed and disposed so that the blade, upon such swinging thereof, makes contact with the wiper before disengagement from said first-named clip and thereafter makes contact with said separate clip before disengagement from said wiper.
7. A switch, as in claim 6, including a resistor interposed in such shunt circuit.
